UNITED STATES PATENT OFFICE.

ABRAM L. REESE, OF WILMORE, KANSAS.

THRESHING-MACHINE ATTACHMENT.

1,011,370.

Specification of Letters Patent. Patented Dec. 12, 1911.

Application filed August 30, 1911. Serial No. 646,770.

To all whom it may concern:

Be it known that I, ABRAM L. REESE, a citizen of the United States, residing at Wilmore, in the county of Comanche and 5 State of Kansas, have invented a new and useful Threshing-Machine Attachment, of which the following is a specification.

By way of explanation I will state that in certain grain weighers for threshing machines, and notably in that device which is 10 known in the trade as the "Peoria Weigher," the gate of the hopper is controlled by a trip arm, which, in its turn, is actuated by the scale beam of the weigher, the scale 15 beam operating a friction clutch which is operatively connected with the trip arm. The friction mechanism which thus controls the action of the gate of the hopper, soon becomes worn and does not connect the 20 operative parts of the machine promptly, when the scale beam rises. As a result, the operation of the weigher lags behind the tilting of the scale beam, with a consequent inaccuracy in the weight of the grain delivered. 25

The present invention aims to provide a novel form of spring means for imparting an initial actuation to the trip arm of a grain weigher for a threshing machine, 30 whereby, so soon as the trip arm is set free for movement by the friction clutch of the weigher, there will be no lagging of the trip arm.

With the foregoing and other objects in 35 view which will appear as the description proceeds, the invention resides in the combination and arrangement of parts and in the details of construction hereinafter described and claimed, it being understood 40 that changes in the precise embodiment of invention herein disclosed can be made within the scope of what is claimed without departing from the spirit of the invention.

In the accompanying drawings,—Figure 45 1 shows the invention in perspective, assembled with portions of the weighing mechanism of a threshing machine; Fig. 2 is a side elevation of the cut-off mechanism; Fig. 3 is a perspective of the clamp which 50 serves, in connection with a fixed abutment, to hold one end of the spring as the other end of the spring is engaged with the trip arm; and Fig. 4 is a side elevation of one end of the supporting member which carries the spring whereby the trip arm is 55 actuated.

Since the present invention contemplates no essential changes in the present forms of grain weighers, the device herein disclosed being merely an attachment for such weighers, the construction of the weigher itself will be touched upon but briefly, only such parts thereof being described as are necessary for a complete understanding of the operation of the structure for which patent 60 protection is desired.

In the accompanying drawings, the numeral 1 denotes the hopper of a grain weigher for a threshing machine. The cut-off mechanism for the hopper 1 comprises a 65 gate 2, carried by a lever of the first order, the lever including converging arms 3 supporting the gate 2, and an operating rod 4, connected with the arms 3 at their place of union. At the point where the operating 70 rod 4 is bifurcated to form the arms 3, the lever is fulcrumed, as shown at 5.

Pivottally connected, as at 6, with the operating rod 4, is a longitudinally adjustable trip arm 7, pivottally connected at one 75 end with a crank pin 8 carried by a crank arm 9 secured to a shaft 10. The numeral 80 11 denotes the scale beam of the weigher, and the construction of the device is such that when the scale beam 11 tilts, friction 85 mechanism (not shown) is automatically connected with the shaft 10 to actuate the same, the construction being such, when the device is in perfect working order, that when the scale beam 11 tilts, the shaft 10 will be 85 operated, thereby moving the crank arm 9 and the trip arm 7, the trip arm 7 actuating the lever 4—3, the gate 2 being thereby moved with respect to the hopper 1. As 90 hereinbefore pointed out, the friction drive 95 for the shaft 10 soon becomes worn, and the movement of the gate 2 lags behind the movement of the scale beam 11. To correct this difficulty, I have devised the mechanism 95 hereinafter set forth and claimed.

The invention comprises a supporting member, preferably taking the form of a rod 12, formed at one end with a flattened, spring eye 14, the free end 15 of which lies against one side of the rod, as clearly shown 100 in Fig. 4. In the inner edge of the eye 14, adjacent the free end 15 of the eye, there is a notch 16, adapted to receive a loop 17 formed at one end of a retractile, helical spring 18, the spring 18 surrounding the 105 rod 12. The eye 14 constitutes a means whereby the rod 12 may be connected piv-

otally with the crank pin 8, the free end of the rod 12 being slidably supported by mechanism which will now be described.

As clearly shown in Fig. 3, the invention 5 includes a clamp denoted generally by the numeral 19, the clamp embracing a pair of jaws 20, pivotally connected adjacent one end, as shown at 21. The jaws 20 are overlapped upon each other, and in their adjacent edges, notches 22 are formed, the notches 22 defining an opening 23 through the clamp 19. A securing element 24 is passed through the free ends of the jaws 20, the securing element 24 carrying a wing 10 nut 25 or the like. The rod 12 rides freely in the opening 23, but the spring 18 is engaged by the jaws 20. An abutment plate 26 is provided, the ends 27 and 28 of which are angularly disposed. The spring 18 and 15 the rod 12 are movable in the end 27 of the abutment plate, the end 28 being secured by means of bolts 29 or the like to the register casing 30 of the weighing machine. The end 27 of the abutment plate 26 is located 20 between the clamp 19 and the trip arm 7, and thus, through the coöperation of the clamp 19 and the end 27 of the abutment plate, one end of the spring 18 is held, so that the spring may exert a tension upon 25 the eye portion 14 of the rod 12, and consequently upon the trip arm 7. By shifting the clamp 19 along the spring 18, the tension of the spring may be adjusted, it being obvious that the jaws 20 may be separated 30 for this purpose, by removing the securing element 24.

In practical operation, so soon as the scale beam 11 tilts, thereby connecting the friction mechanism (not shown) with the 40 shaft 10, the spring 18 will exert a pull upon the rod 12, the rod 12 serving thus to tilt the trip arm 7. Consequently, the trip arm 7 will be actuated initially, so soon as the scale beam 11 tilts, even though the 45 aforementioned friction clutch mechanism should lag somewhat in engaging the shaft 10 whereby the crank arm 9 and the trip arm 7 are actuated.

From the foregoing it will be seen that a 50 simple mechanism is provided whereby the cut-off structure including the gate 2 will be actuated promptly, when the scale beam 11 tilts.

Having thus described the invention, what 55 is claimed is:—

1. In a device of the class described, cut-off mechanism; a trip arm operatively connected with the cut-off mechanism; a rod

pivoted to the trip arm; a retractile spring surrounding the rod and connected thereto; 60 a clamp in which the rod is adapted to slide, the clamp being engaged with the spring; and a fixed abutment adapted to engage the clamp.

2. In a device of the class described, cut-off mechanism; a trip arm operatively connected with the cut-off mechanism; means for actuating the trip arm; a rod pivotally connected with the trip arm; a retractile spring surrounding the rod and connected thereto; 70 a clamp comprising pivotally connected parts, adapted to engage the spring, and to receive the rod slidably; and a fixed abutment adapted to engage the clamp.

3. Mechanism for initially actuating the 75 trip arm of a weighing device, said mechanism comprising a rod having means to engage the trip arm; a spring surrounding the rod and connected thereto; a clamp engaging the spring, in which clamp the rod is 80 slidable; and an abutment member surrounding the spring and adapted to receive the clamp.

4. Mechanism for imparting an initial actuation to the trip arm of a weighing machine, said mechanism comprising a rod having means to engage with the trip arm; a spring surrounding the rod and secured thereto; a clamp comprising pivotally connected parts, adapted to engage the spring 90 and to receive the rod slidably; and an abutment member through which the spring and the rod pass, and against which the clamp abuts.

5. Mechanism for imparting an initial actuation to the trip arm of a weighing machine, said mechanism comprising a rod formed at one end with an eye adapted for connection with the trip arm; a spring surrounding the rod and engaged at one end 100 with the eye; a clamp comprising pivotally connected parts adapted to engage the spring, in which parts the rod is adapted to slide; means uniting the parts of the clamp, to hold the same engaged with the spring; and an abutment member through which the rod and the spring pass, the abutment member being adapted to engage the clamp.

In testimony that I claim the foregoing as my own, I have hereto affixed my signature 110 in the presence of two witnesses.
